UNITED STATES PATENT OFFICE.

JOHN ROLAND WILKINS, OF MAYO, AND STEPHEN W. SHUFORD, OF SPARTANBURG, SOUTH CAROLINA.

ERASING DEVICE FOR TYPEWRITERS.

Application filed May 9, 1925. Serial No. 29,089.

The present invention relates to erasing devices for typewriters, and aims to provide a novel and improved device for conveniently and quickly erasing a character immediately after it has been printed by a typewriter, for making a correction or change quickly and without having to turn the platen.

Another object is the provision of novel means for mounting an eraser on a typewriter and for operating it, so that the eraser is normally out of the way without obstructing vision of the work being done, and operable to bring said eraser into action for erasing a character immediately after being printed by simply pushing down a key.

A further object is the provision of such an erasing device operable in combination with the back spacing means of the typewriter, whereby the platen may be set back by the back spacer as usual simultaneously with the operation of the erasing device, in order that a correction or change may be made quickly and conveniently immediately after a character has been printed, and the back spacer being operable independently of the erasing device if desired.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a front view of the device with the eraser shown in operative position in full lines and in normal idle position in dotted lines, and the back spacer and eraser levers being shown in cross section on the line 1—1 of Fig. 2.

Fig. 2 is a plan view of the device, portions being broken away, and the eraser guide being shown in section on the line 2—2 of Fig. 1.

Fig. 3 is a side elevation of the back spacer and eraser levers.

Fig. 4 is a front view of a modified construction, corresponding with Fig. 1, and omitting the key levers.

Fig. 5 is a section on the line 5—5 of Fig.

4, showing the key levers, portions being broken away and the platen being shown diagrammatically.

In carrying out the invention there is provided a clamp 7 to fit on or embrace a suitable portion of the frame 8 of a typewriter, and said clamp is secured to the frame by set screws 9 or otherwise. A bracket 10 has a pivot portion 11 seated on the clamp 7 and pivotally connected with and clamped on said clamp by means of a pivot and clamping screw 12 threaded downwardly into the clamp and on which the portion 11 is mounted for rotary movement. The bracket 10 projects in front of the roller platen 13 of the typewriter, and by loosening the screw 12 the bracket 10 may be adjusted toward and away from the platen in order that the device will operate properly. As shown, the clamp 7 is at the right hand side of the typewriter, with the bracket 10 projecting toward the left. This bracket is provided at its inner end with a curved guide 14 to guide the eraser to and from operative position.

A lever or bar 15 is pivoted, as at 16, on the bracket 10 near the clamp 7 and is provided at its free end with a U-shaped portion 17 straddling the guide 14. A shaft 18 is journaled in the portion 17 in rear of the guide 14 and carries the eraser 19, which is a disk of rubber or other suitable abrasive material. A friction or gear pinion 20 is secured on said shaft within the portion 17 to bear against the rear side of the guide 14, and the eraser 19 is located beyond the end of the lever 15 and projects rearwardly to contact with the paper on the platen at the point where the type contacts with the paper. A roller 21 is mounted in the portion 17 to bear against the front side of the guide 14, so that the free end of the lever 15 moves smoothly along the guide 14. The pinion 20 may frictionally contact with the guide 14 to rotate the eraser 19 when the lever 15 is oscillated, or gear teeth may be formed on the pinion 20 and rear side of the guide 14.

The back spacer lever of the typewriter is indicated at 22, being fulcrumed as at 23 and having the back spacer button or key 24 which when depressed will, through the back spacing means (not shown), set the platen backwardly, as well known. The

erasing lever 25, as shown, is mounted on the same fulcrum 23 as the back spacer lever, and is disposed adjacent to said lever, and carries a button or key 26 to be depressed 5 when making an erasure. The lever 25 is connected by a link 27 or other suitable connection with the lever 15, so that the lever 15 is swung downwardly by the depression of the eraser lever 25. The operative connection 10 between the levers 15 and 25 may vary with different makes of typewriters.

In order that the back spacer lever will be depressed with the eraser lever, and to permit the back spacer lever to be depressed 15 without depressing the eraser lever, a piece or member 28 is secured to the lever 25 and is slotted to straddle the lever 22. Thus, when the lever 25 is depressed the piece 28 will also depress the lever 22, but the lever 22 may be depressed without moving the lever 25 downwardly.

The back spacer lever 22 being normally raised by its spring 29 will raise the piece 28 and lever 25, and the link 27 being raised 25 will raise the lever 15 to dotted line position shown in Fig. 1. The eraser 19 will therefore be raised out of the way so as not to obstruct the vision of the work being done.

The back spacer may also be operated without 30 operating the erasing device. When it is desired to make a correction or change after printing a character, the eraser button or key 26 is depressed, which will depress the back spacer lever 22 so as to set 35 the platen back to the position it occupied when the character was printed. At the same time, the lever 15 is swung downwardly and the pinion 20 rolling along the guide or rack 14 will rotate the eraser 19. Said 40 eraser comes into tangential contact with the paper on the platen and is rotated when approaching and contacting with the paper, so as to erase the character from the paper. The erasure is thus accomplished by the 45 simple depression of the key or button 26, and when said button is released the erasing device and back spacer lever return to normal position. By holding the back spacer key 24 down, the erasing device may 50 be operated several times, if desired, without operating the back spacer.

In the modified construction shown in Figs. 4 and 5, the bracket 10' is of different form, but is clamped for swinging adjustment 55 on the clamp 7 in the same manner as the bracket 10. The bracket 10' has a depending arcuate guide 14, and a bearing 15' is pivoted, as at 16', to the bracket 10'. A combined shaft and lever 18' carries the 60 disk-shaped eraser 19 at one end and has its opposite terminal swivelled for rotation in the bearing 15', whereby said shaft may be rotated as well as swung upwardly and downwardly in a vertical plane substantially 65 parallel with the axis of the

platen and spaced from said platen at the front side thereof. The shaft rotates about its axis in the bearing 15' and swings upwardly and downwardly about the pivot 16'. A combined roller and bearing 20' is fitted 70 on the shaft 18' and is adapted to roll along the guide 14' to guide the shaft 18' for upward and downward movement, and the guide 14' has a hook 20' at its lower end into which the roller 20' seats when the shaft 75 18' is moved downwardly to erasing position. A yoke 17' straddles the roller 20' and engages the shaft 18' loosely, and a retractile coiled spring 21' is connected to the yoke 17' and bracket 10' in order to 80 raise the shaft 18' and lift the eraser 19 out of the way when the device is not in use.

The back spacer lever 22 and eraser lever 25 are the same as hereinbefore described, but the operative connection between the 85 lever 25 and eraser shaft 18' is different. Thus, a cord or flexible element 27' is wound around, as at 30, the shaft 18' near the bearing 15', and one end is connected to a retractile coiled spring 31 anchored to the 90 frame. The other end of the cord 27' is connected operably with the lever 25. As shown, a secondary lever 32 is located below the lever 25 to which the cord 27' is connected, the lever 32 being fulcrumed, as 95 at 33, in front of the pivot 23. The lever 32 has a finger or lug 34 against which the lever 25 contacts, whereby the depression of the lever 25 will swing the free end of the lever 32 down through a greater distance to pull the cord 27' down sufficiently for the intended purpose.

The spring 21' normally raises the shaft 18' to the dotted line position as shown in Fig. 4, with the eraser 19 raised out of the 105 way. By depressing the lever 25, the lever 32 is swung downwardly to pull the cord 27' downwardly. The first slight downward movement of the cord 27' will swing the shaft 18' downwardly to erasing position 110 substantially parallel to the axis of the platen 13 (full line position as seen in Fig. 4), thereby bringing the edge of the eraser 19 into contact with the platen or paper thereon. The roller 20' seats in the hook 20', thereby limiting the downward movement of the eraser, and the further or continued downward movement of the cord 27' will then rotate the shaft 18' so as to rotate the eraser while in contact with the 115 paper. The wound portion 30 of the cord gripping the shaft will rotate the shaft by the downward pull on the cord 27', and the spring 31 is stretched. In this way, when the cord 27' is started downwardly the eraser is moved from idle to operative position, and is then rotated by the further or continued downward movement of the cord 27'. This enables the eraser to be rotated 120 while in contact with the paper so as to ob-

125

tain a clean erasure. When the lever 25 is released, the spring 21' will restore the parts to normal idle position.

Having thus described the invention, what is claimed as new is:—

1. The combination with the roller platen and frame of a typewriter, of an erasing device comprising a shaft, a disk-shaped eraser thereon, a bracket, means for adjustably supporting said bracket from said frame to adjust the bracket toward and away from the platen, means mounting said shaft on said bracket for the rotation of the shaft about its axis and for the swinging movement of said shaft in a plane spaced to one side from said platen, said shaft being adapted to swing in said plane to a position substantially parallel with the axis of said platen with the eraser contacting at its edge with the platen or paper thereon, and operating means for swinging said shaft in said plane and rotating said shaft about its axis.
2. An erasing device for typewriters comprising a shaft, a disk-shaped eraser secured thereon, means for mounting said shaft for rotation about its axis and for swinging movement to and from erasing position, yieldable means for normally swinging said shaft away from erasing position, and operating means including a flexible element wound on said shaft and an elastic spring connected to said element, whereby when said flexible element is pulled it will swing said shaft to erasing position and rotate the shaft.
3. An erasing device for typewriters comprising a bracket having a guide, a bearing pivoted to said bracket, a shaft journaled in said bearing and adapted to swing with the bearing to and from erasing position, a disk-shaped eraser secured on said shaft, a roller mounted on the shaft and movable along said guide, yieldable means for swinging said shaft away from erasing position,

and means connected to said shaft for swinging it to erasing position and rotating said shaft.

4. An erasing device for typewriters comprising a bracket having a guide, a bearing pivoted to said bracket, a shaft journaled in said bearing to swing therewith to and from erasing position, a disk-shaped eraser secured on said shaft, a roller on the shaft movable along said guide, a yoke straddling said roller and engaging said shaft, a spring connecting said yoke and bracket for yieldingly swinging the shaft away from erasing position, and operating means including a flexible element wound on said shaft and an elastic spring connected to said flexible element, whereby when said element is pulled it swings the shaft to erasing position and rotates said shaft.

5. An erasing device for typewriters comprising in combination with a back spacer lever, an eraser lever, erasing means operatively connected with said eraser lever to be operated thereby and adapted to operate at the point where the type impressions are made, and means for moving the back spacer lever with the eraser lever and permitting the back spacer lever to be operated by itself.

6. An erasing device for typewriters comprising in combination with a back spacer lever, an eraser lever, erasing means operatively connected with said eraser lever to be operated thereby and adapted to operate at the point where the type impressions are made, and a member secured to one of said levers to contact with the other for moving the back spacer lever with the eraser lever and permitting the back spacer lever to be operated by itself.

In testimony whereof we hereunto affix our signatures.

JOHN ROLAND WILKINS.
STEPHEN W. SHUFORD.
